FIRST AID CABINET WITH DRAWER OPENING REINFORCING FRAME

Louis P. Mancini, 129 Braiburn Road,
Florham Park, N.J.
Filed Oct. 27, 1961, Ser. No. 148,153
3 Claims. (Cl. 312—336)

This invention relates to portable first aid cabinets, preferably formed from molded plastic material, wherein the casing of the cabinet is formed with a minimum number of wall to wall partitions to economize on the structure of the cabinet. More particularly, the invention deals with a cabinet structure, wherein all of the walls at the front of the casing are recessed for reception of a reinforcing or supporting frame defining part of the cross-sectional contour of the several drawer compartments of the cabinet.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a diagrammatic front view of a cabinet made according to my invention, illustrating the reinforcing frame supported in the recessed portions of all of the walls of the cabinet and illustrating the drawers arranged in the compartments defined by the contour of the frame and part of the walls of the cabinet.

FIG. 2 is a section on the line 2—2 of FIG. 1 showing the front portion only of the cabinet; and

FIG. 3 is a partial section on the line 3—3 of FIG. 1. In illustrating one adaptation and use of my invention, I have shown at 10 the casing of a cabinet of the character defined, the casing having top and bottom walls 11 and 12, side walls 13 and 14 and a back wall 15, note FIG. 3. The side walls 13 and 14 are integrally united with upper and lower partition walls 16 and 17 which are the only partition walls constituting part of the casing 10 of the cabinet. The forward edge portions of the walls 11 and 12 have, centrally thereof, notches 11' and 12' extending substantially one-third the length of the walls 11 and 12. Similar notches are formed centrally of the forward edges of the side walls 13, 14, as indicated at 13' and 14'. Further, the two partition walls 16 and 17 are recessed at their edges as indicated at 16', 16"; 17', 17", the recesses 16', 16"; 17', 17" registering with the notches 13', 14'.

At 18 I have shown one of my reinforcing and supporting frames, generally of cross-shape peripheral contour, the frame having rail portions 19 and 20 fitting in the notches or recesses 11', 12', the rail portions 21 and 22 fitting in the notches or recesses 13', 14', rail portions 23 and 24 fitting in the notches 16', 16" and rail portions 25, 26 fitting in the notches 17', 17". The frame 18 further includes parallel rail portions 27 integrally uniting the rail portion 19 with the rail portions 23 and 24. The frame includes further parallel rail portions 28 integrally uniting the rail 20 with the rail portions 25 and 26.

It will, thus, be seen that, when the frame 18 is arranged in the notches of the several walls of the casing 10 and cemented or otherwise fixed therein to form an integral part of the casing, the complete casing is divided into three upper drawer compartments 29, 30 and 31, three lower drawer compartments 32, 33 and 34, the compartments being defined by the rails of the frame 18 and the walls of the casing 10. The two series of three drawer compartments are spaced by one horizontally long drawer compartment 35, which is primarily formed between the walls 13, 14 and the partition walls 16 and 17. It will,

2

thus, be understood that the rails 23, 24, 25 and 26 are in alignment with the forward edges of the partitions 16 and 17.

From the foregoing, it will be apparent that the cabinet or the two series of three drawer compartments are formed in one horizontally long compartment at the upper and lower portions of the casing, in other words, similar to the drawer compartment 35.

Arranged in the drawer compartments 29 to 34, inclusive, are drawers 36, preferably of the same size; whereas, one wide drawer 37 is arranged in the compartment 35. All of the drawers 36 have fingergrip knobs 38; whereas, the drawer 37 has a single fingergrip knob 39. Each of the drawers 36 includes front wall portions 40 which are set inwardly with respect to the forward edge of the casing 10 and the exposed surface of the frame 18 so that the fingergrip knobs, integral therewith, will be contained within the forward edges of the casing in order that a suitable cover, not shown, can be applied to the casing to close the entire front thereof when the drawers are in closed position. Each drawer 36 also includes a bottom wall 41 integral with the wall 40 and a back wall 42 integral with the bottom wall 41, the back wall being preferably of less height than the front wall 40, as will clearly appear from a consideration at the lower portion of FIG. 3.

The drawer 37 is generally of the same cross-sectional form as the drawers 36, in other words, includes an inwardly set front wall 43, a bottom wall 44 and a back wall 45.

The drawer 37 is guided in its movement inwardly and outwardly through the casing by the side walls 13 and 14. However, to guide the drawers 36 in their inward and outward movement, the partition wall 16 is grooved in alignment with the rails 27, as seen at 46 in FIG. 3, for reception of guide rails or strips 47 projecting sufficiently to guide the bottom wall 41 of the upper series of drawers 36 in their movement into and out of the casing 10. The bottom wall 12 is similarly grooved, as seen at 48, for reception of guide rails or strips 49, which are in alignment with the rails 28 of the frame 18.

In FIG. 2 of the drawing, a plan view of a part of the two strips 47 is shown to clearly illustrate their alignment with the rails 27 of the frame 18.

From the foregoing, it will be apparent that, by virtue of the method of constructing the cabinet, the same can be very economically produced, keeping in mind that the casing 10 includes only the two horizontal partition walls 16 and 17. These divide the interior of the casing into three large horizontal compartments. The frame 18 is formed as an independent product and is placed in and secured in the notched or recessed forward edges of all of the walls of the casing with the outer edge of the frame in alignment with the corresponding edges of the walls of the casing 10. This operation of securing the frame 18 in position is performed after the strips 47 and 49 have been cemented or otherwise fixed in the grooves 46 and 48. It will also be apparent that the several drawers employed are of economical construction and, by standardizing on the size of the drawers 36, then only two drawer sizes are necessary to complete the entire cabinet structure.

The cabinet is further of such size as to contain the essentials mostly used in rendering first aid treatment such as, for example, sterile bandages, cotton, adhesive tape, finger bands, sterile gauze pads, standard types of remedies for treatment of wounds and burns and such hardware as essential, the latter being stored in the large central drawer 37 of the cabinet.

Having fully described my invention, what I claim as new and desire to secure by Letters Patent is:

1. A cabinet comprising a casing defined solely by

integral top, bottom, back and side walls and by a pair of horizontal partition walls extending between the side walls and spaced from the top and bottom walls, the horizontal partition walls dividing the cabinet into top, middle and bottom drawer sections, the front of the casing being open, parts of the forward edge portions of the top, bottom, side and partition walls being recessed, a reinforcing frame comprising integrally joined horizontal and vertical rails, portions of said vertical rails being mounted and secured in the recesses of said side walls, all of the horizontal rails being mounted and secured in the recessed portions of all of the horizontal walls, and other portions of the vertical rails of said frame dividing the open front of the top and bottom sections of the casing into a plurality of drawer receiving compartments.

2. A cabinet as defined in claim 1, wherein the bottom wall of the casing and one of the partition walls have drawer guide strips fixed thereto in alinement with the last named portions of the vertical rails of said frame for guidance of drawers mounted in the casing.

5

3. A cabinet as defined in claim 1, wherein the outer front surfaces of the frame are in alinement with front edges of all of the walls of the casing.
